UNITED STATES PATENT OFFICE.

CHARLES E. ROSS, OF COLUMBUS, OHIO.

BRICK-HANDLING MACHINE.

1,234,493.

Specification of Letters Patent. Patented July 24, 1917.

Application filed May 15, 1916. Serial No. 97,501.

To all whom it may concern:

Be it known that I, CHARLES E. Ross, a citizen of the United States, residing at Columbus, in the county of Franklin and State of Ohio, have invented certain new and useful Improvements in Brick-Handling Machines, of which the following is a specification.

This invention relates to brick handling machines and is designed particularly as a labor saving means in the production of brick.

The main object of my invention resides in structures whereby the amount of manual handling is reduced to a minimum, by means of which the percentage of loss is greatly reduced.

In this connection, it is one of the objects of my invention to provide mechanism whereby the green bricks are arranged on pallets and these pallets in turn arranged in superposed relation in such manner that they may be readily engaged while in such superposed relation for transportation to the kiln and also deposited in the kiln without being touched by the hands of the workmen.

Other objects of my invention reside in the structure whereby the bricks are placed on the pallets, the bricks and the pallets arranged in superposed relation with each other, and the means for engaging and transporting them after they have been arranged in such superposed relation. These objects I accomplish by means of the structures shown in the accompanying sheets of drawings, in which similar characters of reference designate corresponding parts, and in which:

Figure 1 is an assembly view shown somewhat diagrammatically of the mechanism referred to above,

Fig. 2 is a view in side elevation showing one end of a rotary cutting machine combined with a machine for placing the cut bricks on pallets and moving these pallets onto a conveyer structure,

Fig. 3 is an enlarged view showing the pallet delivery machine more in detail,

Fig. 4 is a section taken on line 4—4 of Fig. 3 and looking in the direction of the arrows,

Fig. 5 is a view of one of the details shown in Figs. 3 and 4,

Fig. 6 is a view of the structure shown in Fig. 5 and taken at right angles thereto,

Fig. 7 is a front view of the conveyer structure used for arranging the pallets and bricks in superposed relation,

Fig. 8 is a side view of the structure shown in Fig. 7,

Fig. 9 is a cross section taken through the conveyer chains and showing the supporting tray in its proper relation,

Fig. 10 is a front view of the carrier structure used in transporting the bricks and pallets to the kiln,

Fig. 11 is a section taken on line 11—11 of Fig. 10, and,

Fig. 12 is a view in perspective of one of the spacer blocks used for properly spacing the pallets from each other.

In Fig. 2, I have shown one end of a rotary cutting machine of a well known construction, comprising a rotatably mounted gear wheel 1, carrying a plurality of rearwardly projecting rods 2 onto one end of which wires 3 are secured. The opposite ends of these wires are secured to the rod 4 which is arranged centrally with respect to the gear wheel 1 in such relation that, when the gear wheel is turned, these wires pass through the slots 5 of a sectional table 6, the various sections of which are rigidly held in position by means of brackets 7 also mounted on the shaft 4. As is customary, this machine is mounted in such relation with the auger machine (not shown) with the clay ribbon coming therefrom, passes over the table 6 and is severed into the proper sections. As is well known, the cutting machine is moved forward at the same rate of speed as the travel of the clay ribbon during the cutting operation and after the cutting operation is again withdrawn to its starting position. The wires 3 are intermittently moved to pass through the clay ribbon, the structure for effecting this being well known and being confined within the housing 8 and driven by the gears 9 and 10. The power shaft is shown at 11 and is provided with a pulley 12 and pinion 13, the latter being designed to mesh with the teeth of the gear wheel 1 and being of such face that will permit the reciprocatory movement of the cutting machine without disengaging the teeth of this gear 1. The mechanism thus far described is of well known construction and does not form a portion of this invention.

Mounted in co-operative relation with this cutting machine is a pallet delivery machine

2
shown in Figs. 2, 3 and 4. This pallet delivery machine comprises a general framework 14 mounted upon rollers 15. This general framework is rigidly connected with 5 the cutting machine by means of the tie connection shown at 16, so that movement of the cutting machine will also cause a corresponding movement of the pallet delivery machine. The shaft 11 for driving the cutting machine is continued and united with a driving shaft 11^a of the pallet delivery machine by means of the squared end shown at 17 and the square socket 18 on the end of the shaft 11. The speed of the shaft 11 is suitably reduced by means of the gearing confined within the housing 19 and this shaft 11^a also carries a bevel pinion 20, which meshes with a bevel gear 21 mounted on a shaft 22. This latter shaft is suitably journaled in the framework and also carries a peculiarly shaped cam 23 on its rear end. The purpose of the drive connection thus far related, is to suitably manipulate the table 24 and the pallets 25, as the latter are placed in 25 position. This table plate 24 is rigidly mounted on a pair of slide members 26 mounted to slide laterally between the two ends of the general framework by means of the rollers 27. After a suitable number of 30 bricks have been forced from the cutting table 6 onto the table 24, the portion 28 of the cam 23 becomes effective to permit the table 24 to be moved toward the left of Fig. 4, in which case the upstanding stationary 35 back plate 29 of the framework causes these bricks to be moved onto the pallet 25 or rather, the pallet 25 is moved toward the left to the position occupied by the table plate 24, as shown in Fig. 4, and the bricks 40 are held against movement by the back plate 29 whereby they are placed upon the pallet. The mechanism for accomplishing this movement is as follows: The shaft 30 extends longitudinally of the pallet delivery machine and is suitably journaled in the framework. This shaft is provided with a pair of rearwardly extending arms 31 on which weights 31^a are rigidly secured. A pair of levers 33 are also rigidly secured to 45 the shaft 30 and are connected to the member 32 slidably mounted on the slide members 26 abutting the table 24 by means of a connecting link shown at 33^a. These weighted arms 31 normally tend to move the table 24 50 toward the left, the movement toward the right being controlled by means of the cam 23 and the upstanding arm 34 pivotally mounted at its lower end at 35 and also pivotally connected at its upper end as shown 55 at 36 with a link 37. This latter link is in turn operatively mounted intermediate the ends of the lever 33 as is shown at 38. The arm 34 also rotatably carries a roller 39 intermediate its ends, which roller cooperates 60

with the surfaces of the cam 23. Thus when 65 the portion 28 of the cam passes beneath the roller 39, the arm 34 and the table 24 move rearwardly under the influence of the weights 31^a. This movement causes the bricks to be moved onto the pallet 25 and 70 continued rotation of the cam 23 brings the surface 40 into engagement with the roller 39 to move the table 24 and pallet 25 toward the right. This movement is effected by means of the rollers 41 mounted on the end 75 of the levers 33 engaging the surfaces 42 of the shoulder members 43 rigidly secured to the underside of the table 24. An inspection of Figs. 5 and 6 will show that the surfaces 42 are interrupted at their upper ends by 80 having a portion cut out as shown at 44 and when the table 24 has been moved to assume the position shown in full lines in Fig. 4, the roller 41 is in a position directly opposite these cut out portions. It will, therefore, appear that continued rotation of the cam 23 will cause the rollers 41 to pass through these cut out portions and leave the table 24 in the position shown to receive the on-coming bricks, but will continue to move the slide member 32 whereby continued movement of the pallet 25 is effected. This continued movement of the pallet is to transfer it to a conveyer mechanism, as shown diagrammatically in Fig. 1 and to permit this 85 continued movement, it is necessary that the pallet should be unlocked. Each of the slide members 26 is provided with a dog 45 pivoted intermediate their ends as shown at 46. One end of each of these dogs is also provided with an upstanding lip 47 and the tail portion is provided with a roller 48, which rollers engage the cam surfaces shown 90 at 49. As the table 24 moves toward the left, the rollers 48 will leave surfaces 49 to permit the lips 47 to assume a locked engagement with the pallets 25. Return movement causes these dogs to assume an unlocked position as shown in Fig. 4, as will be readily 95 understood. As soon as these dogs have unlocked the pallet, this pallet is forced off of the slide member 26 as has been related and this movement is accomplished during the time that the cutting machine and, consequently the pallet delivery machine, remains 100 stationary as regards its reciprocating movement or, in other words, it is at the time that the cutting machine has reached one end of its reciprocatory movement.

110 After one pallet 25 has been removed, another is manually placed in position and this occurs just after the one removed is forced onto the conveyer structure shown in Figs. 1, 7 and 8. This conveyer structure 115 comprises a pair of endless chains 50 passing over sprockets 51 and 52 mounted respectively on shafts, 53 and 54. A plurality of trays 55 are pivotally mounted between 120

these chains 50, the bottom portion of each of these trays being offset slightly as is shown at 56. One of these trays is moved to the relative position shown in Fig. 1, 5 whereby the pallet 25 is slid onto the same. After this, the crank 57 on the end of a shaft 58 may be turned to in turn cause rotation of the worm 59 which meshes with a worm wheel 60, which latter is mounted on 10 the end of the shaft 54. This crank is turned a distance sufficient to bring the next succeeding tray to a position opposite the pallet delivery machine and each time a pallet with the bricks thereon is delivered, 15 the conveyer is moved another step whereby the pallets and their bricks are arranged in superposed relation.

After this operation has taken place a sufficient number of times, the side of the 20 conveyer opposite from that to which the pallets are fed, will also be loaded with pallets and bricks, as must be apparent. It is then necessary to remove these pallets and brick and to accomplish this, I have provided the carrier shown in Figs. 1, 10 and 25 11. This carrier comprises a wheeled base 61 carrying upstanding guide frames 62 adjacent one end. Between these guide frames there is mounted a rack frame formed of 30 side pieces 63 and held spaced by means of the spacer rods 64. Each of these slide frames is provided on its rear edge with a series of teeth 65 and along its front edge with a plurality of forwardly projecting 35 horizontally arranged arms 66. The arms 66 are of a height to fit the offset portions 56 of the trays 55 beneath the pallets supported thereon and are also spaced from each other distances equal to the spacing of 40 the trays 55 on the conveyer chains. The carrier is then moved adjacent the conveyer structure so that the arms 66 enter the offset portions 56 of the trays and a slight elevation of the slide frame 63 caused by turning 45 the crank 67 which operates the worm 68, worm wheel 69 and pinions 70, will lift these pallets with their bricks off of their respective trays. Movement of the carrier away from the conveyer structure then entirely frees these pallets from the conveyer 50 and the carrier with its load of bricks and pallets may then be transported to the kiln or any other desired locality, the carrier in the present instance being shown as provided with a counter-weight 71 to prevent overbalancing because of the added weight 55 of bricks and pallets. After these pallets have been thus removed from the conveyer, the blocks shown in perspective in Fig. 12 60 and designated by the reference numeral 72 are placed on the pallets to maintain them in proper spaced relation. Should it then be desired to deposit these bricks and pallets, the crank 67 is turned to lower the slide 65 frames 63 until the lowermost block 72 engages the floor, in which position they will sustain the entire weight of the superposed bricks and pallets and consequently, the arms 66 will come out of engagement with the underside of each of the pallets. The 70 carrier may then be withdrawn and returned to the conveyer structure for another load.

From the foregoing description, taken in connection with the accompanying sheets of drawings, it will be apparent that I have provided an arrangement of structures whereby it is unnecessary for the workmen to themselves handle the brick. In this manner, the edges do not become broken 75 and a vast saving is effected.

The operation is as follows, briefly stated. The clay ribbon is forced over the cutting table and cut into bricks in the usual manner and these bricks eventually are forced 80 onto the table 24 of the pallet delivery machine. The table 24 is moved toward the left of Fig. 4 under the influence of the weights 31^a when the roller 40 passes over the portion 28 of the cam 23. This causes 85 the bricks to be forced onto the pallet 25 and this pallet is held locked on the slide members 26 by means of the pivoted dogs 45. Continued rotation of the cam 23 moves the table 24 toward the right until the rollers 41 on the ends of the arms 33 register with the cut-out portions 44 of the members 43. When these rollers do register, they pass 90 through these cut-out portions to permit the table 24 to remain stationary, but to continue the movement of the pallet 25 toward the right. This pallet is then forced onto one of the trays of the conveyer structure 95 and after the conveyer structure has received the same, the crank 57 is rotated to bring the succeeding tray to an upright position adjacent the pallet delivery machine. This operation is continued and eventually the right hand side of the conveyer structure becomes loaded with bricks 100 and pallets as well as the left hand side. The carrier structure is then moved to a position to bring the arms 66 beneath the pallets and these pallets are removed from the conveyer structure by a slight elevation 105 of the arms 66 caused by turning the crank 67. The carrier is then withdrawn from the position adjacent the conveyer structure and the blocks 72 placed in position. 110

After this, the carrier may be moved to the kiln and after the framework 63 has been lowered a distance sufficient to bring the lowermost block 72 into engagement 115 with the floor, the arms 66 are relieved of the weight of the superposed arrangement of pallets and bricks and the carrier may then be withdrawn. In this manner, the 120

bricks may be carried to the kiln in properly spaced relation ready for firing without having been touched by the workmen.

What I claim, is:

- 5 1. The combination with a cutting machine over which a clay ribbon moves and is cut into bricks, of a pallet delivery machine comprising a table for receiving the bricks and movable transversely of the clay
10 ribbon, means for supporting a pallet in front of and in the same plane with said table, means for forcing the cut bricks from said table onto said pallet, means for locking said pallet in its receiving position, means
15 operable to unlock said pallet after the bricks have been placed thereon, and means for feeding the pallet and bricks away from said table after the pallet has been unlocked.
20 2. The combination with a cutting machine over which a clay ribbon moves and is cut into bricks, of a pallet delivery machine comprising a table for receiving the bricks and movable transversely of the clay
25 ribbon, means for supporting a pallet in front of and in the same plane with said table, means for forcing the cut bricks from said table onto said pallet, means for locking said pallet in its receiving position,
30 means automatically operable to unlock said pallet after the bricks have been placed thereon, and means for then continuing the movement of the pallet but leaving said table stationary.
35 3. The combination with a cutting machine over which a clay ribbon moves and is cut into bricks, of a pallet delivery machine comprising a table for receiving the bricks and movable transversely of the clay
40 ribbon, means for supporting a pallet in front of and in the same plane with said table, a stationary back plate, means for moving said table beneath and to the rear of said back plate, said pallet being also
45 movable with said table, and means for removing said pallet and bricks after the table has been returned to its normal position.
50 4. The combination with a cutting machine over which a clay ribbon moves and is cut into bricks, of a pallet delivery machine comprising a table for receiving the bricks and movable transversely of the clay ribbon, means for supporting a pallet in

front of and in the same plane with said table, means for locking the pallet and table in such relation, a stationary back plate, means for moving said table beneath and to the rear of said back plate its full width with the pallet locked to it, and means for automatically unlocking the pallet and table upon return of the table to normal position. 55 60

5. The combination with a cutting machine over which a clay ribbon moves and is cut into bricks, of a pallet delivery machine comprising a table for receiving the bricks and movable transversely of the clay ribbon, means for supporting a pallet in front of and in the same plane with said table, means for locking the pallet and table in such relation, a stationary back plate, means for moving said table beneath and to the rear of said back plate its full width with the pallet locked to it, means for automatically unlocking the pallet and table upon return of the table to normal position, and means for continuing the movement of said pallet but leaving said table stationary. 65 70 75

6. The combination with a cutting machine over which a clay ribbon moves and is cut into bricks, of a pallet delivery machine comprising a table for receiving the bricks and movable transversely of the clay ribbon, means for supporting a pallet in front of and in the same plane with said table, a slide plate between said table and pallet, a stationary back plate, a lever pivoted at one end, a roller at its other end, a link connection between said last named end and said slide plate, means whereby the roller end of said lever is moved rearwardly to move said table beneath said back plate, said table and pallet being locked together with said slide plate between them, a shoulder member carried by said table having a trackway for said roller, said trackway being notched out at its top, and means whereby said pallet is unlocked from said table at the time said roller reaches said notched out part to permit continued movement of the pallet but leaving the table stationary. 80 85 90 95 100

In testimony whereof I affix my signature
in presence of two witnesses.
